ATTORNEY.

UNITED STATES PATENT OFFICE.

SAMUEL WIEDER, OF NEW KENSINGTON, PENNSYLVANIA.

LIP STENCIL.

Application filed January 24, 1925. Serial No. 4,469.

To all whom it may concern:

Be it known that I, SAMUEL WIEDER, a citizen of the Republic of Estonia, residing at New Kensington, in the county of Westmoreland and State of Pennsylvania, have invented certain new and useful Improvements in Lip Stencils, of which the following is a specification.

This invention is for a stencil for use in applying cosmetics or make-up to the lips.

The invention has for its object to provide a device in the nature of a stencil, which may be conveniently held against the upper lip with one hand, while a lip-stick is rubbed over the lip, whereby only the desired portion of the lip can be quickly and easily colored without the painstaking effort now generally required.

A further object of the invention is to provide a device of this nature which may be flexed within restricted limits, to conform to the requirements of the individual user, and which may be easily kept clean.

The nature of the invention may be readily understood by reference to the accompanying drawings, in which:

Fig. 1 is a view representing the manner in which the article is used;

Fig. 2 is a top view of the article;

Fig. 3 is a plan view thereof; and

Fig. 4 is a perspective view of the article.

The article, which is preferably made of celluloid or similar resilient or flexible material, has a substantially flat main portion 5, and inwardly curled ends 6 forming finger holds for the device. The article has a suitably shaped lower edge 7, preferably of "Cupid bow" configuration, while the upper edge 8 may have any suitable shape. The width of the sheet is ample to give strength, while the thickness is not too great to render it unduly stiff. It may be thickened at the ends so as to give rigidity to the finger holds 6, as indicated at 8.

In use, it is pressed against the upper lip 45 by the spread thumb and forefinger of one hand, leaving uncovered that portion of the upper lip to which the cosmetic is to be applied. A lip stick or other cosmetic may then be easily and quickly applied, the space 50 between the spread thumb and forefinger giving ample room and vision for applying the lip stick. As only the exposed part of the lip will receive the paint, a sharp symmetrical outline can be almost instantly 55 formed. By raising or lowering the stencil, which is fairly long, and by suitable flexing thereof, the device can be suited to a wide mouth or to a small one.

From the foregoing, it may be seen that 60 the article greatly facilitates the amplification of coloring or make-up to the lips.

I claim as my invention:

1. A lip stencil comprising a bendable plate having finger-holds thereon, and a lip-shaped stencil edge on the plate. 65

2. A lip stencil comprising a substantially flat plate having curled-up ends providing finger-holds, one edge of the plate having 70 the outline of an upper lip.

3. A lip stencil comprising a celluloid plate having turned-up ends providing finger-holds, one edge of the plate having the outline of an upper lip. 75

4. A lip stencil comprising a celluloid body having integral turned-up ends, the thickness of the end portions of the plate being thicker than the main body of the plate to impart greater rigidity to the turned-up portions, one edge of the plate conforming to 80 the outline of an upper lip.

5. A lip stencil comprising a celluloid plate having a stencil edge of lip-shaped formation, and finger-holds at each end of 85 the plate.

In testimony whereof I affix my signature.

SAMUEL WIEDER.
